(57) **ABSTRACT**

An exercise machine may include a frame, a base portion of the frame, a deck pivotally connected at a rear end, an upright structure of the frame, a handle movably attached to the frame, and a linkage connecting the handle to the first end of the deck. An elevation of the first end of the deck changes when the handle is moved.

BODY WEIGHT LIFT MECHANISM ON TREADMILL**RELATED APPLICATIONS**

This application claims priority to U.S. Patent Application Ser. No. 62/415,933 titled "Body Weight Lift Mechanism on Treadmill" and filed on 1 Nov. 2016, which application is herein incorporated by reference for all that it discloses.

BACKGROUND

Aerobic exercise is a popular form of exercise that improves one's cardiovascular health by reducing blood pressure and providing other benefits to the human body. Aerobic exercise generally involves low intensity physical exertion over a long duration of time. Typically, the human body can adequately supply enough oxygen to meet the body's demands at the intensity levels involved with aerobic exercise. Popular forms of aerobic exercise include running, jogging, swimming, and cycling, among others activities. In contrast, anaerobic exercise typically involves high intensity exercises over a short duration of time. Popular forms of anaerobic exercise include strength training and short distance running.

Many choose to perform aerobic exercises indoors, such as in a gym or their home. Often, a user will use an aerobic exercise machine to perform an aerobic workout indoors. One type of aerobic exercise machine is a treadmill, which is a machine that has a running deck attached to a support frame. The running deck can support the weight of a person using the machine. The running deck incorporates a conveyor belt that is driven by a motor. A user can run or walk in place on the conveyor belt by running or walking at the conveyor belt's speed. The speed and other operations of the treadmill are generally controlled through a control module that is also attached to the support frame and easily within reach of the user. The control module can include a display, buttons for increasing or decreasing a speed of the conveyor belt, controls for adjusting a tilt angle of the running deck, or other controls. Other popular exercise machines that allow a user to perform aerobic exercises indoors include elliptical trainers, rowing machines, stepper machines, and stationary bikes, to name a few.

One type of treadmill is disclosed in U.S. Pat. No. 7,575,537 issued to Joseph K. Ellis, et al. In this reference, an exercise treadmill is described as having an endless movable surface looped around rollers or pulleys to form an upper run and a lower run, the movable surface being rotated when one of the rollers or pulleys is rotated, and an exercise surface for walking or running while exercising, a weight resistance mechanism for providing a weight resistance for simulating the dragging or pulling of a load, wherein the weight resistance can be adjusted and set to a specific weight resistance setting; a movable hand controller operatively attached to the weight resistance mechanism for operating and controlling the exercise treadmill and the weight resistance mechanism. According to Ellis, the endless movable surface moves in a direction simulating walking or running backwards, and the weight resistance mechanism applies a constant and static force to the hand controller generally only in the same as the direction the endless movable surface moves and opposite a pulling direction. In this manner, according to Ellis, operation of the treadmill simulates the dragging or pulling of a load by a combination of the actuation of the weight resistance mechanism to simulate the load and the walking or running backwards to provide the

dragging or pulling action. Other treadmills are described in U.S. Patent Publication Nos. 2007/0232463 issued to Yu Feng Wu and 2015/0352396 issued to William T. Dalebout.

SUMMARY

In one embodiment, an exercise machine includes a frame, a base portion of the frame, a deck pivotally connected at a rear end, an upright structure of the frame, a handle movably attached to the frame, and a linkage connecting the handle to the first end of the deck. An elevation of the first end of the deck changes when the handle is moved.

The exercise machine may also include a first post of the upright structure, a second post of the upright structure, an axle connecting the first post to the second post, and the handle rotates about the axle.

The first post may be connected to the base portion, the second post may be connected to the base portion, and the deck may move independent of the first and second post when the handle is moved.

The exercise machine may include a torque adjuster that changes the mechanical advantage between the handle and the linkage.

The exercise machine may include a connection plate, an opening defined in the connection plate, and the axle may be disposed within the opening.

The exercise machine may include linkage slots defined in the connection plate where the linkage slots selectively connect to an end of the linkage.

The linkage slots may be arranged in a generally linear arrangement.

The linkage may be pivotally connected to the first end of the deck.

The exercise machine may include handling slots defined in the connection plate where the handle slots selectively connect to at least one of the handles.

The handle slots may be arranged in a generally semi-circular arrangement.

The exercise machine may include a sleeve disposed about the axle and at least one of the handles may be rigidly connected to the sleeve.

The exercise machine may include a locking assembly, a housing of the locking assembly rigidly connected to the sleeve, and a retractable pin of the locking assembly partially disposed within an aperture of the housing.

The retractable pin may be aligned with at least one of the handle slots by rotating the sleeve.

The exercise machine may be a treadmill.

In one embodiment, a treadmill includes a frame, a base portion of the frame, a deck pivotally connected to the frame at a rear end, a first pulley at a first end of the deck, a second pulley at a second end of the deck, a tread belt surrounding the first pulley and the second pulley, an upright structure of the frame, a handle movably attached to the frame, a linkage connecting the handle to the first end of the deck, wherein an elevation of the first end of the deck changes when the handle is moved, a first post of the upright structure, a second post of the upright structure, an axle connecting the first post to the second post where the handle rotates about the axle when the handle rotates, the first post is connected to the base portion, the second post is connected to the base portion, the deck moves independent of the first and second post when the handle is moved, and a torque adjuster that changes the mechanical advantage between the handle and the linkage.

The treadmill may also include a connection plate, an opening defined in the connection plate, and the axle may be disposed within the opening.

The treadmill may include linkage slots defined in the connection plate where the linkage slots may selectively connect to an end of the linkage.

The exercise machine may include handling slots defined in the connection plate where the handle slots selectively connect to at least one of the handles.

The exercise machine may include a sleeve disposed about the axle and at least one of the handles may be rigidly connected to the sleeve.

In one embodiment, a treadmill includes a frame, a base portion of the frame, a deck pivotally connected to the frame at a rear end, a first pulley at a first end of the deck, a second pulley at a second end of the deck, a tread belt surrounding the first pulley and the second pulley, an upright structure of the frame, a handle movably attached to the frame, a linkage connecting the handle to the first end of the deck, wherein an elevation of the first end of the deck changes when the handle is moved, a first post of the upright structure, a second post of the upright structure, an axle connecting the first post to the second post, the handle rotates about the axle when the handle rotates, the first post is connected to the base portion, the second post is connected to the base portion, the deck moves independent of the first and second post when the handle is moved, a torque adjuster that changes the mechanical advantage between the handle and the linkage, a connection plate of the torque adjuster, an opening defined in the connection plate, the axle being disposed within the opening, linkage slots defined in the plate, wherein the linkage slots selectively connect to an end of the linkage, handle slots defined in the plate, wherein the handle slots selectively connect to at least one of the handles, a sleeve disposed about the axle, at least one of the handles being rigidly connected to the sleeve, a locking assembly, a housing of the locking assembly rigidly connected to the sleeve, and a retractable pin of the locking assembly partially disposed within an aperture of the housing.

BRIEF DESCRIPTION OF THE DRAWINGS

FIG. 1 depicts a cross-sectional perspective view of an example of an exercise machine in accordance with aspects of the present disclosure.

FIG. 2 depicts a side view of an example of an exercise machine in accordance with aspects of the present disclosure.

FIG. 3 depicts a side view of an example of an exercise machine in accordance with aspects of the present disclosure.

FIG. 4 depicts a perspective view of an example of a torque adjuster in accordance with aspects of the present disclosure.

FIG. 5 depicts a perspective view of an example of a connection between a deck and linkage of an exercise machine in accordance with aspects of the present disclosure.

FIG. 6 depicts a side view of an example of an exercise machine in accordance with aspects of the present disclosure.

FIG. 7 depicts a side view of an example of an exercise machine in accordance with aspects of the present disclosure.

FIG. 8 depicts a perspective cross-sectional view of an example of an exercise machine in accordance with aspects of the present disclosure.

FIG. 9 depicts a perspective cross-sectional view of an example of an exercise machine in accordance with aspects of the present disclosure.

FIG. 10 depicts a perspective cross-sectional view of an example of an exercise machine in accordance with aspects of the present disclosure.

10 FIG. 11 depicts a side view of an example of an exercise machine in accordance with aspects of the present disclosure.

15 FIG. 12 depicts a cross-sectional view of an example of an exercise machine in accordance with aspects of the present disclosure.

DETAILED DESCRIPTION

For purposes of this disclosure, the term “aligned” means 20 parallel, substantially parallel, or forming an angle of less than 35.0 degrees. For purposes of this disclosure, the term “transverse” means perpendicular, substantially perpendicular, or forming an angle between 55.0 and 125.0 degrees. Also, for purposes of this disclosure, the term “length” 25 means the longest dimension of an object. Additionally, for purposes of this disclosure, the term “width” means the dimension of an object from side to side. Often, the width of an object is transverse the object’s length. Further, for purposes of this disclosure, the term “post” generally refers 30 to an upright structural member.

FIG. 1 depicts a cross-sectional view of an example of a treadmill 100 that includes a deck 102, a base 104, and an upright structure 106. The deck 102 includes a front pulley connected to a front portion, and a rear pulley connected to 35 a rear portion. A tread belt 108 surrounds a portion of the deck, the front pulley, and the second pulley. A motor (not shown) can drive either the front pulley or the rear pulley and cause the tread belt 108 to move along a surface of the deck 102. The deck 102 may be movably connected to the 40 base 104. For example, the deck may be pivotally connected at a rear portion of the base 104.

In this example, the upright structure 106 includes a first post 110 and a second post 112. The first post 110 and the second post 112 support an axle 114 that spans from the first 45 post 110 to the second post 112. A pair of handles 116 is connected to the axle 114. In this example, the handles 116 protrude away from the axle 114 and are angled towards the deck 102. A user can move the handles 116 so that the connecting end 118 of the handles 116 rotates about the axle 114.

A torque adjuster 120 is rigidly connected to the handles 116 so that when a user moves the handles 116, the torque adjuster 120 rotates with the handles 116. In this example, the torque adjuster 120 includes multiple openings. A first subset of openings are the handle openings 122. These handle openings 122 are used to interlock the handles 116 to the torque adjuster 120. The angle at which the handles 116 protrude away from the axle 114 depends on which of the handle openings is interlocked with the handles 116.

60 A second subset of openings defined in the torque adjuster 120 are linkage slots 124. The linkage slots are spaced along the bottom side of the torque adjuster 120 and selectively interlock with a linkage 128. The linkage 128 may connect the torque adjuster 120 to the deck 102. As the user moves the handles 116, the torque adjuster 120 rotates with the handles 116. As the torque adjuster 120 rotates, the linkage 128 moves with the torque adjuster 120 resulting in movement of

the deck. For example, when a user lifts up on the handles 116, the front portion of the deck 102 moves up. Similarly, when the user moves the handles 116 downward, the deck 102 is also lowered.

A deck pin 130 is incorporated into at least one of the first post 110 and the second post 112. The deck pin 130 is movably retained in the post and can selectively interlock with the connection plate. The deck pin 130 may be insertable into any desired opening of the connection plate. With the deck pin 130 interlocked with the connection plate, the connection plate is selectively locked into place with respect to the post. As a result, the angle of the deck may be locked in place. In some cases, the handles may be disengageable from the connection plate. When the handles are interlocked with the connection plate and the deck pin is interlocked with the connection plate, then the handles may be locked in place. But, in those circumstances where the handles are disconnected from the connection plate, the handles may be moveable without affecting the orientation of the deck.

FIG. 2 illustrates an example of a treadmill 200 with a body weight lift mechanism 202. In this example, a user 204 stands on the deck 206 of a treadmill 200 in a hunched position. The deck 206 is aligned with the base 208 of the treadmill 200. The handles 210 are angled downwards towards the deck 206. The linkage 212 is connected to the linkage slot 214 nearest to the user 204.

FIG. 3 illustrates an example of a treadmill 300 with the body lift mechanism. In this example, the user 302 is standing on the deck 304 in an upright position after having been in the hunched position. The user 302 continues to hold the handles 306 while transitioning from the hunched position to the upright position. As the user 302 stands, the handles 306 are lifted from a lower elevation to a higher elevation 308. As the handles 306 rotate, the torque adjuster 310 is also rotated upwards, which applies an upward force on the linkage slot 312 interlocked with the linkage 314. As a result, the linkage 314 and the front portion of the deck 304 are also lifted upwards. With the user 302 standing on the deck 304, the user's body weight provides resistance to lifting the deck 304.

FIG. 4 illustrates an example of a torque adjuster 400 of the body weight lift mechanism. In this example, the upright structure's post 402 is connected to the axle 404. The handles 406 may be rigidly connected to the axle 404. In this example, the torque adjuster 400 is rotationally independent of the axle so that the torque adjuster 400 can rotate about the axle 404. In another example, the handles 406 may be connected to a sleeve 405 disposed about the axle 404. In those examples with a sleeve, the torque adjuster 400 may be rigidly connected to the sleeve so that the torque adjuster 400 is rotationally independent of the axle 404.

The torque adjuster 400 includes a connection plate 408. In this example, the connection plate 408 includes handle openings 410 and linkage slots 412. The handle openings 410 are located in an upper portion 414 of the connection plate 408, and the linkage slots 412 are located in a lower portion 415 of the connection plate 408.

In the illustrated example, the handle openings 410 are connected to a first end 416 of the handle 406. The handle 406 extends away from the axle 404 towards the user standing on the deck. The user can grip the second end of the handles 406 while standing on the deck. As the user pulls up on the second end of the handle 406, the connection plate 408 is rotated around the axle 404.

The handle openings 410 are located within a medial region 420 of the connection plate 408. The lower portion 415 of the connection plate 408 has a length that is greater

than a length of the plate's upper portion 414. Thus, the lower portion 415 extends beyond the upper portion 414 lengthwise. The linkage slots 412 are distributed from side to side on the lower portion 415 of the connection plate 408. As a result, the linkage slots 412 extend beyond the plate's medial region 420 and therefore extend beyond the handle openings. The distance between the handle opening 410 connected to the handle 406 and the linkage slot 412 connected to the linkage 422 defines a torque length 424 or moment arm. The greater the distance between these openings, the greater the torque length. In some examples, there is a negative relationship between the difficulty of lifting the handle 406 and the torque length 424 so that the shorter the torque length the greater load required to lift the deck.

The connection plate 408 has two groups of linkage slots 412. The first group 426 is on the user side 428 of the connection plate 408. The second group 430 of linkage slots 412 is on the far side 432 of the connection plate 408. The first group 426 and the second group 430 are separated by the axle 404. In some examples, when the user lifts up on the handle 406, the user side 428 of the connection plate 408 rotates in an upward direction and the far side 432 of the connection plate moves in a downward direction. Thus, in these types of examples, the user may connect the linkage 422 to the linkage slots 412 in the user side 428 when desiring to perform an exercise that exerts energy in the upward direction. In this example, the deck will be raised as the user lifts up on the handle 406. In other cases, when the user desires to perform an exercise that involves exerting a downward force, the user may connect the linkage 422 into the linkage slots 412 on the far side 432 of the connection plate 408.

The linkage 422 includes a first end 434 and a second end. The first end 434 may be connected to the connection plate 408, and the second end may be connected to the deck.

In this example, the connection plate 408 includes an axle opening 436, and the axle 404 is partially disposed within the axle opening 436. The handle openings 410 are disposed about the axle opening 436. The axle 404 is supported by the first post 402 and the second post (not shown in FIG. 4).

In the illustrated example, a locking assembly 438 is connected to the handle 406. The locking assembly 438 may include a retractable pin 440 that is located within a channel 442 of the handle 406. In the illustrated example, the channel 442 is defined within a column 444 (e.g., a housing) attached to the handle 406. In this example, the column 444 is welded to the outer surface of the handle 406. Alternatively, the channel 442 may be defined in a thickness of the handle 406. In some cases, the retractable pin 440 may be spring loaded or otherwise biased to keep the retractable pin 440 in an extended position when at rest. While this example depicts the channel being directly connected to the handle 406, in other examples, the channel is formed or otherwise attached to the axle 404.

FIG. 4 also depicts the first end 434 of the linkage 422 being connected within a linkage slot 412. The connection between the linkage 422 and the linkage slot 412 may also include a retractable pin, but any appropriate type of connection mechanism may be used in accordance with the principles of the present disclosure.

FIG. 5 depicts an example of the second end 500 of the linkage 502 being attached to the deck 504. This connection 506 is a rotatable connection to accommodate the angle changes between the linkage 502 and the deck 504 as the linkage 502 moves the deck 504.

FIG. 6 depicts an alternative example where the first post 600 and the second post are not rigidly connected to a base

frame. In this example, the deck **602** is raised and lowered by the movement of the handles **604**, and the deck moves independently of the first and second posts. In the illustrated example, the user **606** is in a hunched position and gripping the handles **604**. In this example, a track **606** is defined along the length of the posts **600**. A guide **608** of the deck **602** is fitted within the track **606**. As the user causes the deck **602** to move, the guide **608** stabilizes the movement of the deck **602** with respect to the posts **600**.

FIG. 7 depicts the alternative example with the user **700** standing upright on the deck **702** and with the deck **702** pulled up to an elevated position **704**.

FIG. 8 depicts an example of the treadmill **800** with an alternative connection plate **802**. In this example, the connection plate **802** includes just linkage slots **804** without the handle openings. In this example, the torque length is measured between the axle **806** and the connected linkage slot **804**. Further, the connection plate **802** includes a fewer number of linkage slots **804** than depicted in the other examples. In this case, linkage slots **804** are only depicted on the user side **808** of the connection plate **802**.

In the illustrated example, the treadmill **800** includes a single connection plate **802** on a single side of the treadmill **800**. In alternative examples, the treadmill includes multiple connection plates **802**. For example, a connection plate may be included on both side of the treadmill so that the loads generated from lifting the deck **810** are equalized on both sides of the deck **810**.

FIG. 9 depicts an example of the treadmill **900** where no torque adjuster is included between the handle **902** and the linkage **904**. The treadmill **900** still includes the handle **902** which is indirectly connected to the deck **906** so that the deck position changes as the handle **902** is moved.

FIG. 10 depicts an example of a treadmill **1000** with handles **1002** that have an adjustable length **1004**. In this example, the handles **1002** may include a telescoping portion **1006**. The position of the handles' second end **1008** depends on the length of the telescoping portion. In some examples, the longer the telescoping portion, the farther away the handles' second ends are located from the axle. The farther away the handles' second ends are, the easier it may be to lift the deck.

FIG. 11 illustrates an example of a treadmill **1100** with the body lift mechanism. In this example, the angle of the deck **1102** can be oriented into an upright position independent of the orientation of the handle **1104**. The handles **1104** can be disconnected from the connection plate **1106** by moving the retracted pin (440, FIG. 4). With the handles disconnected, the handles can rotate about the axle to any appropriate location without affecting the deck's angle.

A deck pin **1108** incorporated into the posts **1110** may interlock with the connection plate **1106**. The deck pin **1108** may be incorporated into any appropriate opening defined in the connection plate **1106**. As described above, the deck's angle is affected by the angle of the connection plate **1106**. Thus, as the connection plate **1106** is moved so that the deck pin **1108** is connected into the desired opening, the deck angle also changes. With the deck pin **1108** secured to the connection plate **1106**, the deck angle is locked in place. In some examples, a user moves the connection plate **1106** so that the deck is oriented at the desired angle. While the deck is at the desired angle, the deck pin is inserted into the desired opening to lock the deck at the desired angle. With the deck at the desired angle, the retractable pin is retracted thereby unlocking the handles to rotate about the axle. With the handles freed, the handles can be rotated out of the way from the deck.

FIG. 12 illustrates a cross section view of the treadmill **1100** depicted in FIG. 11. In this example, the deck pin **1108** is incorporated into the post **1110** and interlocks with the connection plate **1106**. The deck pin **1108** may be incorporated into any appropriate opening defined in the connection plate **1106**. With the deck pin **1108** secured to the connection plate **1106**, the deck angle is locked in place. In some examples, the deck pin **1108** is aligned with the axle **1112** that rotationally connects the post **1110** to the connection plate **1106**.

GENERAL DESCRIPTION

In general, the invention disclosed herein may provide users with a treadmill that allows the user to simultaneously or separately perform aerobic exercises as well as lifting exercises. The user's own body weight can provide the resistance to the lifting exercises. In some cases, the mechanical advantage of the lifting mechanisms can be adjusted allowing the user to have a different amount of resistance for different types of lifting exercises. In some cases, the user's own body weight may be too much for the user, so the user can adjust the mechanical advantage to lower the amount of resistance needed to perform the lifting exercise. In some cases, the exercise machine may be used for pushing exercises that involve pushing the handles towards the deck.

At least one handle may be connected to an upright structure of the exercise machine. The handle may be indirectly connected to the deck so that when the handle is moved that the deck's elevation is changed. The handle may be located so that the user can conveniently grasp the handle when the user is standing on the deck.

The deck may include a first pulley located in a front portion of the deck and a second pulley located in a rear portion of the deck. A tread belt may surround the first and second pulleys and provide a surface on which the user may exercise. At least one of the first pulley and the second pulley may be connected to a motor so that when the motor is active, the pulley rotates. As the pulley rotates, the tread belt moves as well. The user may exercise by walking, running, or cycling on the tread belt's moving surface. In other examples, the tread belt is moved with the user's own power. In these situations, the tread belt may move as the user pushes off of the tread belt with his or her feet while walking or running. A flywheel may be connected to the tread belt and/or one of the pulleys to maintain the tread belt's momentum under the user's power.

The deck may be capable of having its front portion raised and lowered as well as its rear portion raised and lowered to control the lengthwise slope of the running deck when the tread belt is moving. The lengthwise slope of the deck may be controlled electronically through controls located in the treadmill or through instructions received from a wireless device. With these elevation controls, the orientation of the running deck can be adjusted as desired by the user or as instructed by a programmed workout. In those examples where the treadmill simulates a route that involves changes in elevation, the running deck can be oriented to mimic the elevation changes in the route while the user performs an exercise on the deck.

In one example, the lengthwise slope and/or lateral tilt angle of the deck can be controlled with one or more actuators, often linear actuators, positioned at the corners of the deck. In another example, a single linear actuator positioned underneath the deck is attached to the deck's underside and a base of the deck. In this example, when the single

linear actuator extends, the single linear actuator increases the incline angle of the deck and when the single linear actuator retracts, the single linear actuator decreases the incline angle of the deck. In yet other examples, multiple actuators are used to adjust the incline angle simultaneously. Other types of actuators may be used, such as cam surfaces, magnets, hydraulic actuators, pneumatic actuators, other types of actuators, or combinations thereof. Thus, in response to determining that the running deck's orientation should change, a signal can be sent to the actuators to appropriately move the deck into the desired orientation. The signal may come from the user's input, a simulated environment, a programmed workout, a remote device, another type of device or program, or combinations thereof.

In some examples where actuators change the slope of the deck, the deck may be detachable from the actuators when the user is performing the lifting exercises. In other examples, the actuators may move with the deck as the user performs lifting exercises with the deck by moving the handles.

In some cases, the user may change the elevation of the front portion of the deck while the user is running by moving the handles. The user may desire to do repetitive lifts while running. In other examples, the user may desire to change the elevation of the deck while running. The user may accomplish this by moving the handles to a desired elevation and locking the handles in place. With the handles locked in place, the elevation of the deck will be fixed. Thus, the user may change the slope of the deck for aerobic exercises with the use of the handle.

In another example, the deck's angle of orientation can be changed independent of the orientation of the handle. The handles can be disconnected from the connection plate by moving the retracted pin away from the connection plate. With the handles disconnected, the handles can rotate about the axle to any appropriate location without affecting the deck's angle.

A deck pin incorporated into the posts may interlock with the connection plate. The deck pin may be incorporated into any appropriate opening formed in the connection plate. As described above, the deck's angle is affected by the angle of the connection plate. Thus, as the connection plate is moved so that the deck pin is aligned for insertion into the desired opening, the deck angle also changes. With the deck pin secured to the connection plate, the deck angle is locked in place. In some examples, a user moves the connection plate so that the deck is oriented at the desired angle. While the deck is at the desired angle, the deck pin is inserted into the desired opening thereby locking the deck at the desired angle. With the deck at the desired angle, the retractable pin may be retracted away from the connection plate thereby unlocking the handles from the connection plate, which frees the handles for rotation about the axle. With the handles freed, the handles can be moved out of the way from the deck. In this example, a user may exercise on the deck at an inclined angle without the handles in the user's immediate vicinity.

The treadmill may include a console attached to an upright structure of the treadmill. In some cases, the upright structure includes a first post adjacent to a first side of the deck and a second post adjacent to a second side of the deck. In this example, the console is supported by the first and second posts. The deck moves independently of the first and second posts and also moves independently of the console.

The console may locate a display screen and the treadmill's controls within a convenient reach of the user to control the operating parameters of the deck. For example,

the console may include controls to adjust the speed of the tread belt, adjust a volume of a speaker integrated into the treadmill, adjust an incline angle of the running deck, adjust a decline of the running deck, adjust a lateral tilt of the running deck, select an exercise setting, control a timer, change a view on a display of the console, monitor the user's heart rate or other physiological parameters during the workout, perform other tasks, or combinations thereof. Buttons, levers, touch screens, voice commands, or other mechanisms may be incorporated into the console and can be used to control the capabilities mentioned above. Information relating to these functions may be presented to the user through the display. For example, a calorie count, a timer, a distance, a selected program, an incline angle, a decline angle, a lateral tilt angle, another type of information, or combinations thereof may be presented to the user through the display.

The treadmill may include preprogrammed workouts that simulate an outdoor route. In other examples, the treadmill has the capability of depicting a real world route. For example, the user may input instructions through the control console, a mobile device, another type of device, or combinations thereof to select a course from a map. This map may be a map of real world roads, mountain sides, hiking trails, beaches, golf courses, scenic destinations, other types of locations with real world routes, or combinations thereof. In response to the user's selection, the display of the control console may visually depict the beginning of the selected route. The user may observe details about the location, such as the route's terrain and scenery. In some examples, the display presents a video or a still frame taken of the selected area that represents how the route looked when the video was taken. In other examples, the video or still frame is modified in the display to account for changes to the route's location, such as real time weather, recent construction, and so forth. Further, the display may also add simulated features to the display, such as simulated vehicular traffic, simulated flora, simulated fauna, simulated spectators, simulated competitors, or other types of simulated features. While the various types of routes have been described as being presented through the display of the control console, the route may be presented through another type of display, such as a home entertainment system, a nearby television, a mobile device, another type of display, or combinations thereof.

In addition to simulating the route through a visual presentation of a display, the treadmill may also modify the orientation of the running deck to match the inclines and slopes of the route. For example, if the beginning of the simulated route is on an uphill slope, the running deck may be caused to alter its orientation to raise the front portion of the running deck. Likewise, if the beginning of the simulated route is on a downward slope, the rear portion of the running deck may be caused to elevate to simulate the decline in the route. Also, if the route has a lateral tilt angle, the running deck may be tilted laterally to the appropriate side of the running deck to mimic the lateral tilt angle.

While the programmed workout or the simulated environment may send control signals to orient the deck, the user may, in some instances, override these programmed control signals by manually inputting controls through the console. For example, if the programmed workout or the simulated environment cause the deck to be steeper than the user desires, the user can adjust the deck's orientation with the controls in the console.

In one example, the upright structure includes a first post and a second post. The first post and the second post support an axle that spans from the first post to the second post. A

11

pair of handles is connected to the axle. In this example, the handles protrude away from the axle and are angled towards the deck. A user can move the handles so that the connecting end of the handles rotates about the axle. While this example has been described with reference to the upright structure including a first post and a second post, other examples of the upright structure may include any appropriate number of posts. In other examples, the upright structure includes just a single post, three posts, or another number of posts. For the purposes of this disclosure, the term post generally refers to a structural element that is oriented upright. In examples where the treadmill includes just a single post, the post may be centrally located with respect to the deck. In other examples with a single post, the post may be positioned off-center with respect to the deck.

A torque adjuster may be rigidly connected to the handles so that when a user moves the handles, the torque adjuster rotates with the handles. In this example, the torque adjuster includes multiple openings. A first subset of openings are the handle openings. These handle openings are used to interlock the handles to the torque adjuster. The angle at which the handles protrude away from the axle depends on which of the handle openings is interlocked with the handles.

A second subset of openings defined in the torque adjuster are linkage slots. The linkage slots are spaced along the bottom side of the torque adjuster and selectively interlock with a linkage. The linkage may connect the torque adjuster to the deck. As the user moves the handles, the torque adjuster rotates with the handles. As the torque adjuster rotates, the linkage moves with the torque adjuster resulting in movement of the deck. For example, when a user lifts up on the handles, the front portion of the deck moves up. Similarly, when the user moves the handles downward, the deck is also lowered.

To perform a lift, the user may be on the deck initially in a hunched position while holding the handles. At the end of the lift, the user may stand in an upright position. The user continues to hold the handles while transitioning from the hunched position to the upright position. As the user stands, the handles are lifted from a lower elevation to a higher elevation. As the handles rotate, the torque adjuster is also rotated upwards, which applies an upward force on the linkage slot interlocked with the linkage. As a result, the linkage and the front portion of the deck are also lifted upwards. With the user standing on the deck, the user's body weight provides resistance to lifting the deck.

The upright structure's post may be connected to the axle that spans from the first post to the second post. The handles may be rigidly connected to the axle so that the axle rotates with the movement of the handles. In other examples, a sleeve is positioned around the axle and the handles are connected to the sleeve. In these examples, when the handle is moved, the sleeve rotates with the handles. In either of these embodiments, when the axle and/or sleeve is rotated by the handle, the rotation of the axle/handle causes the connection plate to move, which in turn causes the linkage and the deck to move.

In some examples, the torque adjuster is rotationally independent of the axle so that the torque adjuster can rotate about the axle. In another example, the handles may be connected to a sleeve (not shown) disposed about the axle. In those examples with a sleeve, the torque adjuster may be rigidly connected to the sleeve so that the torque adjuster is rotationally independent of the axle. In other examples, the torque adjuster is rotationally fixed to the axle so that the axle and the torque adjuster move together.

12

The torque adjuster may include a connection plate. In this example, the connection plate includes handle openings and linkage slots. The handle openings are located in an upper portion of the connection plate, and the linkage slots are located in a lower portion of the connection plate.

In some cases, the handle openings are connected to a first end of the handle. The handle extends away from the axle towards the user standing on the deck. The user can grip the second end of the handles while standing on the deck. As the user pulls up on the second end of the handle, the connection plate is rotated around the axle.

The handle openings may be located within a central region of the connection plate. The lower portion of the connection plate has a length that is greater than a length of the plate's upper portion. Thus, the lower portion extends beyond the upper portion lengthwise. The linkage slots are distributed from side to side on the lower portion of the plate. As a result, the linkage slots extend beyond the plate's central region and therefore extend beyond the handle openings. The distance between the handle opening connected to the handle and the linkage slot connected to the linkage defines a torque length. The greater the distance between these openings, the greater the torque length. In some examples, there is a negative relationship between the difficulty of lifting the handle and the torque length, so that the shorter the torque length the greater the load required to lift the deck.

In some cases, the connection plate has two groups of linkage slots. The first group is on the user side of the connection plate. The second group of linkage slots is on the far side of the connection plate. The first group and the second group are separated by the axle. In some examples, when the user lifts up on the handle, the user side of the connection plate rotates in an upward direction and the far side of the connection plate moves in a downward direction. Thus, in these types of examples, the user may connect the linkage to the linkage slots in the user side when desiring to perform an exercise that exerts a force on the handles in the upward direction. In this example, the deck will be raised as the user lifts up on the handle. In other cases, when the user desires to perform an exercise that involves exerting a downward force on the handle, the user may connect the linkage into the linkage slots on the far side of the connection plate. The linkage may include a first end and a second end. The first end may be connected to the connection plate and the second end may be connected to the deck.

A locking assembly may be connected to the handle, the sleeve, the axle, another component, or combinations thereof. The locking assembly may include a retractable pin that is located within a channel of the handle. The channel may be defined within a column attached to the handle. In this example, the column is welded to the outer surface of the handle. Alternatively, the channel may be defined in a thickness of the handle. In some cases, the retractable pin may be spring loaded or otherwise biased to keep the retractable pin in an extended position when at rest. While the present retractable pin is described as a spring biased pin, any number of selectively actuated pins may be used including, but in no way limited to, a solenoid, a threaded bolt, a detent biased pin, and the like. Additionally, while a pin and correlating holes are described as connecting the handle to the connection plate, any number of engagement systems may be used, including, but in no way limited to, a compression fit, hydraulic engagement members, and cut outs, and the like. While this example has been described with the

channel being directly connected to the handle, in other examples, the channel is formed or otherwise attached to the axle.

Any appropriate type of exercise may be performed with the handles to move the deck with the user's body weight as resistance. A non-exhaustive list of lifts that may be performed under these conditions include squatting exercises, dead lift exercises, curling exercises, military press exercises, bench press exercises, calf raise exercises, jumping exercises, other types of exercises, or combinations thereof. In some cases, a specialized handle attachment may be connectable to the handle's second end that is specialized for a particular type of lift.

While the examples above have been described with a torque adjuster that includes a retractable pin to connect the handles to the connection plate, any appropriate type of connection mechanism may be used in accordance with the principles described herein. For example, the connection mechanism may include a pneumatic mechanism, a magnetic mechanism, a hydraulic mechanism, an electric mechanism, a compression mechanism, an interlocking mechanism, another type of mechanism, or combinations thereof. In examples with an electronic mechanism, a solenoid may be used to move a pin in and out of the openings defined in the connection plate. In another example, a magnet may be used to attach the handles to the connection plate. In this type of example and in other types of examples, the connection plate may not include a handle opening. In some instances, the magnet may attach directly to the plate without an opening. In other examples, a protrusion, grip, or another type of interlocking feature of the locking plate may provide a location for a connection mechanism to attach to the plate so that the handle is connected to the connection plate.

In another example, the torque adjuster does not include a connection plate. In one particular type of example, the handles include a section that can expand so that the length of the handles is changeable. Since the torque applied to the axle is affected by the distance from which the load is applied, the distance of the second end of the handles from the axle affects the torque. The extendable portion of the handles may include a telescoping section, a rail, an expanding material, a screw mechanism, another type of extension mechanism, or combinations thereof.

In another example, the torque adjuster may receive instructions to adjust the torque. In these examples, programmed instructions on the treadmill may cause a processor to adjust the torque. The user may access the instructions to adjust the torque through an input mechanism that is incorporated into the console. In other examples, the user may send the instructions through a remote device, like a mobile device. In further examples, programmed workouts or other programmed instructions may cause the torque to be adjusted without commands being sent from the user.

The linkage may be connected to the deck at any appropriate location. For example, the linkage may be connected to a front portion of the deck, a mid-region of the deck, a rear portion of the deck, another portion of the deck, or combinations thereof.

In some cases, the treadmill may include a belt locking mechanism that locks the tread belt in place when the user lifts the deck by moving the handles. The belt locking mechanism may include a brake. In other examples, the belt locking mechanism may include a feature that interlocks with the belt, the motor, a flywheel, or another component of the deck, or combinations thereof. In some cases, the deck

may be disengaged from the motors, flywheels, other belt drivers, or combinations thereof.

While the examples above have been described with reference to deck pins, retractable pins, and other manually operated pins to selectively change the orientation of the deck, handles, or other treadmill components, any appropriate type of locking mechanisms may be used in accordance with the principles described in the present disclosure. For example, at least one of the pins may be automatically operated. A console, remote device, or other type of user interface may receive input commands from the user to determine the appropriate angles/orientations of the handles, deck, or other treadmill components. In yet other examples, a preprogrammed exercise routine may initiate the angles/orientations of the treadmill components based on the parameters of the preprogrammed workout routine.

The description herein is provided to enable a person skilled in the art to make or use the disclosure. Various modifications to the disclosure will be readily apparent to those skilled in the art, and the generic principles defined herein may be applied to other variations without departing from the scope of the disclosure. Thus, the disclosure is not limited to the examples described herein, but is to be accorded the broadest scope consistent with the principles and novel features disclosed herein.

What is claimed is:

1. An exercise machine, comprising:
a frame;
a base portion of the frame;
a deck pivotally connected to the base portion;
an upright structure of the frame;
a handle movably attached to the frame;
a linkage connecting the handle to the deck, wherein an elevation of the deck changes when the handle is moved; and
a torque adjuster configured to modify a mechanical advantage between the handle and the linkage, the torque adjuster including a connection plate, a lower portion of the connection plate including a lower portion length different from an upper portion length of an upper portion of the connection plate,
wherein the exercise machine comprises a treadmill.
2. The exercise machine of claim 1, further comprising:
a first post of the upright structure;
a second post of the upright structure; and
an axle connecting the first post to the second post;
wherein the handle is rotatably disposed about the axle.
3. The exercise machine of claim 2, wherein
the first post is connected to the base portion;
the second post is connected to the base portion; and
the deck moves independent of the first post and the second post when the handle is moved.
4. The exercise machine of claim 2, further comprising:
an opening defined in the connection plate;
wherein the axle is disposed within the opening.
5. The exercise machine of claim 4, further comprising:
a plurality of handle slots defined in the connection plate;
wherein the plurality of handle slots are configured to selectively connect to the handle.
6. The exercise machine of claim 5, wherein the plurality of handle slots are arranged in a semi-circular arrangement on the connection plate.
7. The exercise machine of claim 6, further comprising:
a sleeve disposed about the axle;
wherein the handle is rigidly connected to the sleeve.
8. The exercise machine of claim 7, further comprising:
a locking assembly;

15

a housing of the locking assembly rigidly connected to the sleeve; and

a retractable pin of the locking assembly partially disposed within an aperture of the housing.

9. The exercise machine of claim 8, wherein the retractable pin is configured to be aligned with at least one of the plurality of handle slots by rotating the sleeve. 5

10. The device of claim 1, further comprising:

a plurality of linkage slots defined in the lower portion of the connection plate;

wherein the plurality of linkage slots are configured to selectively connect to an end of the linkage.

11. The exercise machine of claim 10, wherein the plurality of linkage slots are arranged in a linear arrangement on the lower portion of the connection plate. 15

12. The exercise machine of claim 10, wherein the linkage is pivotally connected to a front end of the deck.

13. The exercise machine of claim 1, wherein the lower portion length is greater than the upper portion length. 20

14. An exercise machine, comprising:

a frame including an upright structure having a first post and a second post;

a deck connected to the frame;

a first pulley disposed at a first end of the deck;

a second pulley disposed at a second end of the deck; 25

a tread belt surrounding the first pulley and the second pulley;

a handle movably attached to the frame;

a linkage connecting the handle to the first end of the deck; and

a torque adjuster that changes a mechanical advantage between the handle and the linkage;

wherein an elevation of the first end of the deck changes when the handle is moved;

an axle connecting the first post to the second post; 35

wherein the handle is configured to rotate about the axle;

wherein the deck moves independent of the first post and the second post when the handle is moved.

15. The exercise machine of claim 14, further comprising:

a connection plate; and

an opening defined in the connection plate;

wherein the axle is disposed within the opening. 40

16. The exercise machine of claim 15, further comprising:

a plurality of linkage slots defined in the connection plate;

wherein the plurality of linkage slots are configured to 45

selectively connect to an end of the linkage.

16

17. The exercise machine of claim 15, further comprising: a plurality of handle slots defined in the connection plate; wherein the plurality of handle slots are configured to selectively connect to the handle.

18. The exercise machine of claim 17, further comprising: a sleeve disposed about the axle; wherein the handle is rigidly connected to the sleeve.

19. An exercise machine, comprising:

a frame including a base portion and an upright structure having a first post and a second post, wherein the first post and the second post are connected to the base portion of the frame;

a deck pivotally connected to the frame at a rear end;

a first pulley at a first end of the deck;

a second pulley at a second end of the deck;

a tread belt surrounding the first pulley and the second pulley;

a handle movably attached to the frame;

a linkage connecting the handle to the first end of the deck;

wherein an elevation of the first end of the deck changes when the handle is moved;

an axle connecting the first post to the second post;

wherein the handle rotates about the axle;

wherein the deck moves independent of the first post and the second post when the handle is moved;

a torque adjuster that changes a mechanical advantage between the handle and the linkage;

a connection plate of the torque adjuster;

an axle receiving opening defined in the connection plate, wherein the axle is disposed within the axle receiving opening;

a plurality of linkage slots defined in the connection plate, the plurality of linkage slots selectively connect to an end of the linkage;

a plurality of handle slots defined in the connection plate, the plurality of handle slots selectively connected to the handle;

a sleeve disposed about the axle, wherein the handle is rigidly connected to the sleeve; and

a locking assembly including a housing and a retractable pin, wherein the housing of the locking assembly is rigidly connected to the sleeve, and wherein the retractable pin of the locking assembly is partially disposed within an aperture of the housing.
